UNITED STATES PATENT OFFICE.

FRANK C. ARMSTEAD, OF NEW YORK, N. Y., ASSIGNOR TO THE WESTINGHOUSE MACHINE COMPANY, A CORPORATION OF PENNSYLVANIA.

FURNACE.

SPECIFICATION forming part of Letters Patent No. 790,339, dated May 23, 1905.

Application filed March 7, 1904. Serial No. 196,966.

To all whom it may concern:

Be it known that I, FRANK C. ARMSTEAD, a citizen of the United States, and a resident of New York, in the county of New York and 5 State of New York, have invented a new and useful Improvement in Furnaces, of which the following is a specification.

My invention relates to furnaces which are provided with mechanical stokers or devices 10 for continuously feeding fuel thereto, and more especially to furnaces of the class referred to which have inclined grates, to the upper ends of which the fuel is fed, fuel-hoppers attached to the metal front walls of the 15 furnaces, and feed - openings in said front walls through which the fuel passes from said hoppers.

The object of my invention is to provide a simple and efficient means for preventing injury 20 to the metal front furnace-wall by heat, one member of which is a sectional throat-plate having special structural and functional characteristics.

In the accompanying drawings, Figure 1 is 25 a view in central longitudinal section of the upper part of a furnace embodying the invention, showing the fuel-hopper, the upper part of the grate, the arch over said grate, the feed-opening, and the associated parts. Fig. 30 2 is a face view of the part of the metal front wall of the furnace shown in Fig. 1 with the fuel-hopper in vertical section. Fig. 3 is a sectional view taken upon line 3 3 of Fig. 1, showing in front elevation the fire-arch and 35 horizontal row of fire-bricks between said fire-arch and the front wall of the furnace. Fig. 4 is an enlarged detail plan section taken on line 4 4 of Fig. 1. Fig. 5 is a detail vertical section of the front wall of the furnace, taken 40 upon line 5 5 of Fig. 4. Fig. 6 is a rear elevation of the parts shown in Figs. 4 and 5 with the fire-bricks removed.

As shown in the drawings, A A indicate the 45 side walls of the furnace; B, the metal front wall thereof; C, the upper part of the inclined grate; D, the fuel-hopper; E, the fire - arch, which extends over the forward part of the

grate, and F F a horizontal row of fire-bricks located between the curved main part of the fire-arch and the front wall of the furnace 50 and which constitutes the forward part of the arch structure.

The grate C, as illustrated, consists of a series of rocking grate-bars arranged in stepped or overlapped relation, and in connection 55 therewith devices may be provided for giving oscillatory or rocking motion thereto; but inasmuch as any form of inclined grate may be employed a detailed illustration thereof is deemed unnecessary. 60

The fire-arch E is inclined downwardly and inwardly in the same general direction as the inclination of the grate below it and is made of stepped form on its under surface, so as to present a plurality of ridges which extend 65 across the furnace and form shoulders or abrupt surfaces facing toward the front of the furnace. The spring of the arch is greater at the inner than at the outer part thereof, or, in other words, the front part of the arch 70 is flatter than the rear part. The arch consists of a series of rows E' to E⁸ of fire-bricks shaped like the voussoirs of an arch and arranged in stepped relation, so as to give a downward and inward inclination to the arch 75 as a whole. The five rows E' to E⁵ of fire-bricks at the forward part of the arch have their under surfaces at the crown of the arch at the same level, but are of gradually-increasing spring or curvature from front to 80 rear, while the rearmost rows E⁶, E⁷, and E⁸ are of uniform spring or curvature.

Referring to the parts more immediately concerned with the present improvements, the feed-hopper embraces two side plates D' D', 85 which are attached to the front wall of the furnace, and a bottom D², which rests upon two inwardly-extending flanges or ledges d d at the lower margins of the side plates. That part of the front wall of the furnace which is 90 below the hopper is formed by plates B' B⁴ B⁴, and the portions of said wall at the ends of the hopper are formed by lateral plates B² B², while the portion above the central part of the

hopper is formed by an intermediate plate B³. The front wall is provided with a feed-opening formed between the plates B', B² B², and B³. The bottom plate D² of the feed-hopper 5 extends inwardly over the plates B' B² B² to form the dead-plate D⁴ and is bolted to the outer surface of said plates B' and B² B². The plates B² B² extend inwardly above the said feed-opening, the intermediate plates B' and 10 B³ below and above the opening being shorter than the width of said opening.

As shown in the drawings, the plate B' is attached at its ends to the plates B² B² by means of vertical connecting-bars b b, bolted 15 to both plates. The lateral plates B² B² are provided with sight-openings b', with poker-doors b², and with offset flanges b³ b³ at their lower edges, which overlap the plates B' B², and are also provided along their vertical 20 edges above the feed-opening with offset flanges b⁴ b⁴, which overlap the ends of the intermediate plate B³ and are bolted thereto. As shown in the drawings, the side plates D' 25 of the hopper are provided with outwardly-extending flanges d' and d'', which are respectively bolted to the lateral plates B² B² above the level of the feed-opening and to the plates B' B² below the level of said opening. The top margin of the feed-opening is formed by 30 a sectional throat-plate consisting of a series of sections G G, which are bolted to the outer faces of the plates B³ and B² B² by bolts g g. Said sections G are provided with rearwardly-extending horizontal flanges G' G', which are 35 transversely corrugated. The plates B³ and B² B², constituting the part of the front wall above the feed-opening, are provided on their rear or inner faces with vertical ribs g' g', and the fire-bricks F F, which fill the space be- 40 tween the curved rear or main part E of the fire-arch and the said front wall of the furnace, are of rectangular form in cross-section and have their outer faces in contact with the ribs g' g', while they rest at their lower edges 45 on and are supported by the corrugated flanges G' G'. In this structure the said fire-bricks F fit closely between the front edge of the front row E' of fire-bricks in the fire-arch and the inner ribbed faces of the plates B² B² and 50 B³ and are held in place by said plates and the curved part of the arch. The spaces or channels between the ribs g' g', together with the depressions or grooves in the upper surfaces of the corrugated flanges G' G', which sup- 55 port the fire-bricks F F, form a series of spaces or passages, as clearly seen in Figs. 4, 5, and 6, through which air is drawn downwardly and inwardly between the said fire-bricks and the front wall of the furnace in 60 order to keep the metal parts above the feed-opening from becoming injured by excessive heat. The construction described has the additional advantage that the fire-bricks F F are not made of special or unusual shape, but

are of ordinary rectangular form and are sup- 65 ported in place merely by being confined between the front wall of the furnace and the front of the curved portion of the fire-arch and without any special supporting means for their rear ends. The external structure of 70 the throat-plate permits of renewal of any section thereof if injured by heat without disturbing the other sections, and the corrugated form of the bottom or supporting flange of the sectional throat-plate reduces its liability 75 to warp under the action of the heat to which it is subjected.

Many of the structural details which I have 80 illustrated and described are not essential and may be therefore varied within considerable limits without departing from my invention.

I claim as my invention—

1. The combination with the metal front wall of a furnace provided with a feed-opening and with vertical ribs on its inner face above said feed-opening, of a throat-plate having an inwardly-extending, horizontal, transversely-corrugated flange, and a plurality of fire-bricks which rest upon said corrugated flange in contact with the said ribs. 90

2. A furnace having a front wall provided with a feed-opening and with vertical ribs on its rear face above said opening and a throat-plate fastened to the said wall at the upper side of the feed-opening and having a rearwardly-projecting, corrugated flange at its lower edge. 95

3. A furnace having a metal front wall provided with a feed-opening and with vertical ribs on its rear face, a throat-plate fastened to said wall at the upper side of the feed-opening and having a rearwardly-projecting, corrugated flange at its lower edge and a row of fire-bricks supported on said flange. 100

4. A furnace having a metal front wall provided with a feed-opening and with vertical ribs on its inner face, above said opening, a sectional throat-plate fastened to said wall above the feed-opening and having a rearwardly-projecting, corrugated flange, and a row of fire-bricks supported upon said flange. 105

5. A furnace having a metal front plate provided with a feed-opening and with vertical ribs on its inner face above said opening, a sectional throat-plate fastened to said front plate above the feed-opening and having a rearwardly-projecting flange and a row of fire-bricks supported upon said flange. 115

6. A furnace having a metal front plate provided with a feed-opening and with vertical ribs on its inner face above said opening, a sectional throat-plate fastened to said front plate above said feed-opening and having a rearwardly-projecting, corrugated flange, a row of fire-bricks resting upon said flange 120 and against said front-plate ribs and a fire-brick arch extending rearwardly from said row of fire-bricks. 125

7. A furnace having a metal front plate provided with a feed-opening and with vertical ribs above said opening, a throat-plate fastened to said front plate above the feed-opening and having ribs on its inner face and a rearwardly-projecting corrugated flange and a row of fire-bricks above said flange.

In testimony whereof I have hereunto subscribed my name this 15th day of February, 1904.

FRANK C. ARMSTEAD.
